UNITED STATES PATENT OFFICE.

LLOYD W. STETSON AND JOSEPH M. THORPE, OF OAKLAND, CALIFORNIA.

DESIGN FOR A TOY VEHICLE-BODY.

53,946.

Specification for Design.

Patented Oct. 7, 1919.

Application filed April 17, 1919. Serial No. 290,873. Term of patent 14 years.

To all whom it may concern:

Be it known that we, LLOYD W. STETSON and JOSEPH M. THORPE, citizens of the United States, residing at Oakland, in the county of Alameda and State of California, have invented a new, original, and ornamental Design for Toy Vehicle-Bodies, of which the following is the specification, reference being had to the accompanying drawing, forming part thereof.

The figure is a view in perspective showing our new design.

We claim as new and wish to cover by Letters Patent:

The ornamental design for a toy vehicle body, as shown.

In testimony whereof we affix our signatures.

LLOYD W. STETSON.
JOSEPH M. THORPE.
